(57) CLAIM

The ornamental design for a housing for electrical breaker, as shown and described.

DESCRIPTION

FIG. 1 is a front right side isometric view of a housing for electrical breaker in accordance with the new design;

FIG. 2 is a right side elevation view thereof;

FIG. 3 is a left side elevation view thereof;

FIG. 4 is a front elevation view thereof;

FIG. 5 is a rear elevation view thereof;

FIG. 6 is a top plan view thereof; and,

FIG. 7 is a bottom plan view thereof.

The broken line portion of the figure drawings is included to show unclaimed subject matter only and forms no part of the claimed design.
